US0D1005673S

(12) **United States Design Patent** (10) **Patent No.:** **US D1,005,673 S**
(45) **Date of Patent:** **** Nov. 28, 2023**

(54) **BACKPACK**

(71) Applicant: **YETI Coolers, LLC**, Austin, TX (US)

(72) Inventors: **Dustin R. Bullock**, Austin, TX (US);
John Loudenslager, Austin, TX (US);
Paul Fair, Denver, CO (US)

(73) Assignee: **YETI Coolers, LLC**, Austin, TX (US)

(*) Notice: Patent file contains an affidavit/declaration under 37 CFR 1.130(b).

(**) Term: **15 Years**

(21) Appl. No.: **29/713,985**

(22) Filed: **Nov. 20, 2019**

(51) LOC (14) Cl. **03-01**

(52) U.S. Cl. **D3/216**
USPC ....

(58) **Field of Classification Search**

USPC **D3/215-218, 221, 224-226, 230-233,**

D3/242-246, 303, 318

CPC **A45F 3/04; A45F 3/047; A45F 2003/045;**

A45F 4/02

See application file for complete search history.

Primary Examiner — Mary Shannon Malley

(74) Attorney, Agent, or Firm — Banner & Witcoff, Ltd.

(57) **CLAIM**

The ornamental design for a backpack, as shown and described.

DESCRIPTION

FIG. 1 is a top, front, right perspective view of a backpack showing our new design;

FIG. 2 is a right side view thereof;

FIG. 3 is a left side view thereof; and,

FIG. 4 is a top, rear, perspective view of a backpack in an alternative configuration thereof.

The broken lines represent portions of the backpack or stitching and form no part of the claimed design.

1 Claim, 4 Drawing Sheets

US D1,005,673 S
